United States Patent Office

Des. 186,024
Patented Sept. 1, 1959

186,024

INSECTICIDE SPRAYER OR THE LIKE

William Martin Vogel, Jr., Mendham, N.J.

Application January 16, 1958, Serial No. 49,276

Term of patent 3½ years

(Cl. D31—3)

Des. 186,024

PAGE 2

Fig. 3.

Figure 1 is a front elevational view of an insecticide sprayer or the like showing my new design;

Figure 2 is a top plan view thereof;

Figure 3 is an elevational view of one side thereof;

Figure 4 is a central vertical sectional view approximately on the plane of the line 4—4 of Figure 2;

Figure 5 is a bottom plan view thereof.

I claim:

The ornamental design for an insecticide sprayer or the like, as shown.
